UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

AUTOMATIC TELEPHONE EXCHANGE.

Application filed October 12, 1917. Serial No. 196,124.

To all whom it may concern:

Be it known that I, FRANK A. LUNDQUIST, a citizen of the United States of America, and a resident of the city of Chicago, county 5 of Cook, and State of Illinois, have invented certain new and useful Improvements in Automatic Telephone Exchanges, of which the following is a specification.

My invention relates to automatic telephone exchanges, and has for its object improvements in such exchanges.

In automatic telephone exchanges, each subscriber has a line switch in the central office and connected to the line which runs 10 to the subscriber's sub-station. At the line switch, and bridged across the line, are two line relays. When a subscriber removes his receiver to make a call, the automatically rising receiver hook closes the two branches 15 of the line at the local station to complete a circuit for the line relays and thereby start the line switch into operation to make a call. Owing to the fact that the line relays are bridged across the ultimate talking 20 circuit, to differences in lengths of lines, and to other circumstances connected with the construction and operation of automatic exchanges, these relays must be high-wound, and usually have a resistance of one thousand ohms or more. This makes those 25 relays the most expensive part of the line switch construction. The main, or central object of the present improvement is to provide means by which one of these expensive 30 line relays serves a plurality of line switches in initiating calls, and is then cut out of the connection so that it is not bridged across the ultimate talking circuit.

The means provided for accomplishing 35 this result consists principally of a special or secondary apparatus which is associated with and serves from five to twenty line switches, the number thus served by this special apparatus being determined in each 40 case by the conditions of traffic to which the exchange is subjected. What is more than this apparatus, consists of some electrical connections to be hereinafter described. As the present improvement does 45 not go beyond the line switches, the draw-

ings and description do not extend beyond making connections to the first selectors and the electrical connections before mentioned. As line relays are common to different forms of line switches, and as the present improvement relates principally to cutting out these 55 relays, the actual construction of the line switch is not material. In the drawings, which are diagrammatic, I have shown a line switch of the drop type, similar in general character to what I have shown in my pending application Serial Number 108,265, filed July 10, 1916, and issued as Patent No. 1,264,826, on April 30, 1918. The restoration of the apparatus to normal position is 60 of the pneumatic type similar to that illustrated in my pending application Serial Number 186,448, filed August 16, 1917.

In the accompanying drawings—

Fig. 1 is a diagram showing two line 70 switches and one secondary apparatus arranged to serve nine such line switches; and

Fig. 2 is a side elevation of one of the drops together with trunks to which it makes connection.

In the said drawings, the first line switch is represented at A, the second at B, and the secondary or special apparatus at C. The lines 5 and 6 of both A and B are the two branches of the line leading from the 75 subscriber's station to his line switch, and across which branches the line relays are bridged in present constructions. These branches terminate in contact springs which are normally pressed upward against stationary contacts by a drop 7 normally held in the position shown in the drawings.

Each line switch has a cylinder 8 and piston 9 normally standing at the lower end of the cylinder. The upper end of each cylinder is connected by a pipe 10 to a vacuum chest (not shown), which connection is normally closed by a valve 11. When this valve is opened, the air in cylinder 8 over piston 9 is drawn out, and the piston 95 rises to restore the apparatus as will be hereinafter described.

In the special or secondary apparatus are a ratchet wheel 12 and disk 13 mounted upon a common shaft represented by dotted 100

lines at 14. On this shaft, and insulated therefrom, are wipers 51 and 47 which are advanced step by step by the ratchet wheel to successive engagement with contact points 5 as will be described later.

There is a bar 15 on which are contact springs 16 arranged to normally close connections to the stationary contact points 15^a which are terminals of wires 25. The bar 15 is connected to a bellows 17, which is the same thing as the well known pneumatic used in player pianos. The pneumatic 17 is connected to a vacuum chest (not shown), which connection is normally closed by a valve 18. The disk 13 has a notch in it which is normally in engagement with the horizontal arm of a bell-crank lever 19 pivoted at 20. The other end of the bell-crank is connected to the valve 18. When the ratchet wheel 12 and disk 13 are advanced, as will be described, the movement of the disk moves the bell-crank 19 to open the valve 18. When this occurs, the pneumatic 17 pulls the bar 15 downward to break all connections made by the springs 16, and to establish a circuit as will be hereinafter described.

The other parts of the apparatus will be understood by a description of the operation.

It will be assumed that the subscriber whose line switch is represented at A, removes his receiver and consequently connects lines 5 and 6 together at his local station. A circuit is then completed as follows: battery X—21—relay 22—23—24—25—26—5—local station—6—28—29—ground—X.

This attracts armature 30, whereupon another circuit is completed as follows: battery X—21—30—31—32—33—34—35—magnet 36—37—ground—X.

Energizing magnet 36 attracts its armature 38 to advance ratchet wheel 12 and the parts secured to shaft 14. The consequent movement of disk 13 operates bell-crank 19 to open valve 18 so that pneumatic 17 will draw down the bar 15 to break the circuit for relay 22 at 16 between 24 and 25. Breaking the circuit for relay 22 permits its armature 30 to fall back and thus break the circuit for magnet 36. Advancing the ratchet wheel 12 moves wiper 51 away from spring 33, which brings about another break at 33—34 in the previously described circuit for magnet 36.

Drawing down bar 15 moves contact spring 41 to connection with contact point 42. This, taken with the simultaneous falling back of armatures 30 and 38, closes a new circuit for magnet 36 as follows: X—21—30—39—40—41—42—43—44—38—45—36—37—ground—X.

When the circuit is so closed, magnet 36

again advances ratchet wheel 12, and at the same times breaks its own circuit at 44. Upon such break the armature 38 falls back to again make the circuit for magnet 36 and again advance ratchet wheel 12. By this means the ratchet wheel is automatically advanced step by step, carrying with it the parts connected to shaft 14.

In the path of wiper 51 is a series of contact points, different ones of which correspond to the different line switches served by the apparatus C. Also, in the path of the wiper 47 is another series of contact points corresponding in the same way to the same line switches. The contact points in the path of wiper 51 are connected to the starting magnets 53 of the different line switches, and those in the path of wiper 47 are connected to the contacts 26 of the different line switches.

When the wiper 47 reaches the contact point connected to 26 of the station which has its relay 22 is completed as follows: battery X—21—22—46—wiper 47—48—25—26—27—5—local station—6—28—29—ground—X.

Thus closing the circuit for relay 22 causes its armature 30 to break the circuit at 39 for magnet 36 and thereby stop the apparatus C with the wipers 51 and 47 on the contacts which correspond to the calling station. This attraction of armature 30 closes a new circuit as follows:—X—21—30—49—50—wiper 51—52—magnet 53—ground—X.

Energizing magnet 53 attracts its armature 54 to release drop 7 so that it may fall to make connection to some idle trunk leading to a selector. In falling, drop 7 permits springs 27 and 28 to move downward to connect the subscriber's line to contacts carried by the drop. In moving downward, spring 27 breaks the circuit at 26 for the relay 22, whereupon the armature 30 falls back and completes a circuit for magnet 36 as before. In this condition, the magnet 36 automatically advances the ratchet wheel 12 and connected parts step by step as before. If, in the mean time, some other local station in the group served by apparatus C has had its receiver removed, circuits will be completed thru wipers 47 and 51 as before to energize magnet 53 of that station's line switch. Otherwise, the magnet 36 will continue to operate until the notch in disk 13 permits bell-crank lever 19 to return to normal position and thus close valve 18. When this occurs the normal air leaks of pneumatic 17 will permit bar 15 to return to normal position, thereby breaking the circuit for magnet 36 at contact 42. This stops the apparatus C until it is started again by some other subscriber in the manner described.

Each drop 7 has pivoted on its side an arm 55 adapted to engage any one of a series of

pivoted bars M which happens to be in its path when the drop falls. When this occurs, the weight of the drop coming upon a bar M swings said bar on its pivot so that it 5 is thereafter out of the path of a similar arm 55 on another drop 7. The same action also moves arm 55 on its pivot to make an electrical connection to an insulated spring 56 connected to wire 52.

10 On the lower end of each drop 7 are wipers 59 and 64 which pass over contacts on trunks N when the drop falls. The trunks N correspond to the bars M so that when a drop 7 falls and is stopped by its arm 55 engaging a bar M in normal position, the wipers 59 and 64 will be in engagement with contact terminals on an idle trunk leading to an idle selector. When this occurs a circuit will be completed as follows:—battery 20 Y—relay 57—58—59—60—61—28—6—local station—5—27—62—63—64—65—66—relay 67—ground—Y.

The relays 57 and 67 are the line relays of a selector switch, and the wipers shown on 25 the end of trunk wires 58 and 65 are the wipers of the same selector. The description so far sets forth the operations involved in reaching a first selector. From this point on, the construction and operations are the 30 same as those in the ordinary exchange.

To make it possible to restore the apparatus to normal position at the end of a conversation, there is a connecting wire 68 from each bar M to the back contact for armature 35 70 of relay 57. This makes connection from battery Y to the magnet 53 thru connections 55—56. To make it certain that this circuit will not be completed at the time the trunk is being selected, the parts 55 and 56 are arranged so that there is a slight delay in completing contact at this point. This gives relay 57 time to break the connection at 40 69—70.

The valve 11 is connected to the upper 45 end of a centrally pivoted lever 71, on the lower end of which is pivoted an arm 72 having a projection 73 and a hook 74. When the parts are in normal position, a lug 75 on drop 7 engages the end of arm 50 72 and holds the projection 73 just above the upper end of armature 54. When magnet 53 is operated to release drop 7, armature 54 passes under projection 73 without touching. When drop 7 falls, lug 75 falls 55 also and permits spring 76 to move arm 72 down against the end of armature 54. When the circuit is broken thru magnet 53, the armature 54 passes to the left of projection so that another attraction of armature 54 will move lever 71 on its pivot to open valve 11, and also will cause hook 74 to engage and be held by a stationary hook 77.

The circuit previously given thru relay

57 is one which is held during talking. When, however, the subscriber hangs up his receiver he breaks the connection between his branches 5 and 6 with the result that armature 70 falls back. When this occurs, a circuit is completed as follows:—Y 70 70—69—68—78—55—56—52—53—ground—Y.

This is the operation which opens the valve 11 and permits vacuum to raise the piston 9. On the piston 9 is a hooked rod 79 which engages a projection 80 on the drop 7 to raise said drop to its normal position. In rising, the circuit for magnet 53 is broken by arm 55 leaving bar 78, but catch 77 is at this time in engagement with catch 74 and holds the valve 11 open. As drop 7 reaches its normal position, lug 75 engages arm 72 to release hook 74 from hook 77. Spring 81 then moves lever 71 to close valve 11. The vacuum connection being no longer on behind piston 9, said piston returns to the normal position shown in the drawings.

I have heretofore referred to the apparatus C as a "secondary" apparatus because it is an addition to other apparatus for eliminating expensive line relays. In a different sense it would be more appropriate to refer to apparatus C as a "primary" apparatus because its operation precedes the actual operation of the line switch in selecting a trunk. The terms "primary" and "secondary," are not here used in opposition to each other, but rather as complementary to each other.

In the present arrangement, the wipers 59 and 64 do not begin their trunk hunting movement immediately upon the subscriber removing his receiver, but do so only after the wipers 47 and 51 of apparatus C have been moved two or more steps from normal position. Normally these operations will occur before the calling subscriber is ready to operate the dial of his calling device, but there are conditions in which there would be delays in apparatus C such that the subscriber would operate the dial before wipers 59 and 64 had found a trunk. Such a condition could arise if three or four subscribers served by the same apparatus C should remove their receivers at substantially the same time. The wipers 47 and 51 would pick these calls up in rotation, but would be delayed in reaching the last one.

To meet these conditions I provide the device shown at D for delivering a tone to the receiver during the interval from the time it is lifted from its hook to the time the drop 7 falls to connect to an idle trunk. This is accomplished by connecting condensers 82 between the lines 25 of the different line switches, and the grounded sec-

ondary 83 of an induction coil which has its primary arranged in a make and break device operated by battery Z. As long as the lines 5 and 6 are connected at the local station, and the drop 7 holds the springs 27 and 28 in their upper position this tone will be heard in the receiver of the calling subscriber. But, upon magnet 53 releasing drop 7, this tone will be cut off by the 10 breaking of the connection at 26.

From the foregoing description it will be seen that there are no line relays bridged between the lines 5 and 6 leading to the line switches. Instead thereof there is one 15 line relay 22 connected in multiple thru 23 and 26 to the lines 5 of a plurality of local stations. The relay 22, together with the other parts of apparatus C, serves all of the purposes of a large number of expensive 20 relays in starting a plurality of line switches into operation.

What I claim is:—

1. In a telephone exchange, the combination with lines leading from a plurality of 25 local stations to a corresponding plurality of line switches at a central office, of a relay connected in multiple to said lines, and devices controlled by said relay for breaking the connection between said relay and said 30 lines and for starting the line switches into operation.

2. The combination with lines leading from a plurality of local stations to a corresponding plurality of line switches at a 35 central office, and a magnet at each line switch for starting such switch into operation, of a relay connected in multiple to said lines and controlled from the local stations, and devices controlled by the relay 40 for closing an electric circuit for the magnet which corresponds to the local station which at the time controls the relay.

3. The combination with a plurality of 45 lines leading from local stations to a central office, and a corresponding plurality of starting magnets located at the central office, of a pair of insulated wipers, means controlled from any local station for advancing said wipers to make connections to lines 50 and corresponding magnets, and means by which the advancing wipers will close an electric circuit for the magnet which corresponds to the line controlling the movement of the wipers.

55 4. The combination with a plurality of telephone lines leading from local stations to a central office, and a relay connected in multiple to said lines and controllable from any one of said local stations, of means for breaking said multiple connection and substituting therefor successive connections between the relay and the lines.

60 5. A plurality of lines leading from local stations to a central office, a relay connected in multiple to said lines, means controlled by

the relay for breaking the multiple connections and substituting therefor connections in rotation from the relay to the lines, line switches associated with the lines, and means controlled from any station for starting 70 the associated line switch into operation when the connections in rotation bring the relay into connection with the station.

6. The combination with a series of subscriber's lines, a corresponding series of line switches, and a starting magnet for each line switch, of a pair of insulated wipers, movable simultaneously over corresponding contact points in the path of each wiper, connections from one set of contact points 80 to the lines and from the other set of contact points to the corresponding starting magnets, a relay serving to start said wipers into movement over their contact points, means by which said relay may be controlled 85 from the local station on any one of said lines, and means by which upon one of said wipers making engagement with the line controlling the relay the other of said wipers will close a circuit for the starting magnet 90 of the corresponding line switch.

7. The combination with a series of subscriber's lines, a corresponding series of trunk selecting devices, and a magnet associated with each trunk selecting device, of insulated wipers, contact points in the paths of the wipers, propelling mechanism for moving said wipers simultaneously over corresponding contact points, connections from one set of contact points to the lines and 100 from the other set of contact points to the corresponding magnets, means controlled from the local station on any one of said lines for starting said propelling mechanism into operation, and means by which upon one of said wipers engaging the contact point connected to the line over which the propelling mechanism was controlled the other of said wipers will complete an electric circuit for the corresponding magnet. 110

8. A plurality of telephone lines, a relay connected in multiple to said lines, automatic means for breaking the multiple connections and substituting therefor connections in rotation from the relay to the lines, and means operating through such rotation for connecting one of said telephone lines to a trunk line. 115

9. The combination with a series of telephone lines, a series of trunk lines, and devices for connecting the telephone lines to the trunk lines, of a pair of insulated wipers, contact points in the path of each wiper, propelling means for moving the wipers to successive engagement with their contact points, connections from one set of contact points to the telephone lines and from the other set of contact points to the connecting devices, and means by which upon one wiper engaging a point connected to a line which is 120 125 130

closed at its local station the other wiper will close a circuit for a connecting device to connect such line to an idle trunk.

10. The combination with a series of telephone lines, a corresponding series of magnets, and trunk selecting devices controlled by said magnets, of devices for automatically closing electrical connections to the lines and corresponding magnets in succession, a battery and means by which upon said devices closing connection to a line which also is closed at its local station said battery will be operatively connected to the corresponding magnet.

15. 11. In a telephone system, a group of lines, a selecting switch for each line, a line relay common to all of said switches and used by each switch in extending a call, said relay normally connected to said lines, and means for disassociating said relay from all the other switches of the group while a connection is being extended from one line and for restoring the relay for use with the other switches while the first connection is maintained.

20. 12. In a telephone system, a group of lines, a line relay common to and normally connected to said lines and usable by any line when extending a connection, and means for preventing more than one line from using said relay at one time.

25. 13. In a telephone system, a group of lines, a line relay common to and normally connected to said lines and usable by any line when extending a connection, means for preventing more than one line from using said relay at one time, and means for connecting a busy signal to any line which initiates a call while said relay is in use by another line.

30. 14. In a telephone system, a plurality of lines, a selecting switch for each line, a line relay normally connected to all of said lines; a controlling device common to said lines controlled by said relay to connect said device in rotation to the lines for use in extending connections therefrom; means for preventing the extension of a connection from any other line while said device is in use by another line, and means for connecting a signal to any line which attempts to call while the device is being so used by another line.

35. 15. In a telephone system, a group of lines, an automatic switch for each line, a line relay common to said switches, a finder switch for connecting said relay to any one of said switches for controlling the operation thereof, said relay operating when a call is initiated from any line to start said finder switch, and operating again to stop the finder switch when the connection is made with the automatic switch associated with the line calling.

40. 16. In a telephone system, a group of

lines, a line relay common to and normally connected to said lines, means for operating said relay from any one of said lines to extend a connection therefrom, and means for disassociating said relay from all the other lines.

45. 17. In a telephone system, a group of lines, a line relay common to and normally connected to said lines, a selecting switch individual to each line, means for operating said relay from any one of said lines for initiating the operation of the selecting switch individual to said one line, and means for disassociating said relay from all the other lines.

50. 18. In a telephone system, a group of lines, a line relay common to and normally connected to said line, a selecting switch individual to each line, means for operating said relay from any one of said lines, means for disassociating said relay from all of said lines to cause said relay to deenergize, means for connecting said relay to said lines in succession and means for again energizing said relay when said one line is found whereby the switch individual to said one line is operated.

55. 19. In a telephone system, a group of lines, a line relay normally connected to all of said lines, a selecting switch for each line normally disconnected therefrom, said relay operated from any line when calling to break its normal connection to all the other lines to find the switch associated with said line and connect it thereto.

60. 20. In a telephone system, a plurality of lines, an automatic switch for each line, a line relay controlled from any of said lines to start the trunk selecting operation of the switch associated with that line, and pneumatically operated means controlled by said relay for disconnecting itself from all other lines while being controlled from any one line.

65. 21. In a telephone system, a group of lines, a relay connected by multiple connections to all the lines of said group and operated from any line to control the extension of a connection therefrom, a pneumatic device for breaking all of said multiple connections, and means controlled by the relay for withdrawing air from said device to cause its operation.

70. 22. In a telephone system, a group of subscribers' lines, automatic switches for extending connections from said lines, a line relay common to and normally connected to all said lines, a finder switch for connecting said relay to any one of said switches for controlling the operation thereof, said relay operating when a call is initiated from any line to start said finder switch, and operating again to stop the finder switch when a connection is made with one of said switches.
